BALL POINT PEN

George G. Larson, Manhattan Beach, Calif., assignor to
Paper Mate Manufacturing Company, Culver City,
Calif., a corporation of Delaware

Application May 23, 1957, Serial No. 46,311

Term of patent 14 years

(Cl. D74—17)

Fig. 1 is a perspective view of a ball point pen, showing my new design;

Fig. 2 is an enlarged fragmentary front elevational view thereof;

Fig. 3 is a like view in side elevation; and

Fig. 4 is a top plan view of the ball point pen shown in Fig. 2.

The essential features of my design reside in the portions shown in solid lines on the drawing.

I claim:

The ornamental design for a ball point pen, as shown and described.
